Primary Examiner — Abraham Bahta(74) *Attorney, Agent, or Firm* — Dunlap Bennett & Ludwig, PLLC(57) **CLAIM**

The ornamental design for a calendar planner, as shown and described.

DESCRIPTION

FIG. 1 is a front elevation view of a first embodiment of a calendar planner, showing my new design.

FIG. 2 is a front elevation view of a second embodiment of the calendar planner.

FIG. 3 is a front elevation view of a third embodiment of the calendar planner.

FIG. 4 is a front elevation view of a fourth embodiment of the calendar planner.

FIG. 5 is a front elevation view of a fifth embodiment of the calendar planner.

FIG. 6 is a front elevation view of a sixth embodiment of the calendar planner.

FIG. 7 is a front elevation view of a seventh embodiment of the calendar planner.

FIG. 8 is a front elevation view of an eighth embodiment of the calendar planner; and,

FIG. 9 is a front elevation view of a ninth embodiment of the calendar planner.

The broken lines shown in the drawings depict portions of the calendar planner that form no part of the claimed design. The calendar planner has no appreciable thickness.
